UNITED STATES PATENT OFFICE

JOHN E. EUTH, OF CHICAGO, ILLINOIS, ASSIGNOR TO UNITED AUTOGRAPHIC REGISTER CO., OF CHICAGO, ILLINOIS, A CORPORATION OF ILLINOIS

TEAR-OFF DEVICE

Application filed March 30, 1931. Serial No. 526,480.

This invention relates to devices for tearing sheet material and particularly to devices for tearing paper sheets or slips used in ordinary business routine.

5 In producing manifold copies for order forms, invoices, shop orders, and the like, it is often necessary that a portion of the form be a label that can be readily cut out of the form itself and applied to the package for 10 shipment.

Heretofore, it has been the practice, in such cases, to perforate around the label portion so that the label can be torn from the form readily. It often happens that the tear 15 does not follow the perforations, and results in the mutilation of the label.

The primary object of the present invention is to provide a simple tear-off device which will permit certain areas of a paper 20 sheet to be torn out very rapidly and conveniently, and obviate any need for perforations or lines of weakening in the sheet itself.

The invention is illustrated in a preferred embodiment in the accompanying drawing, 25 in which—

Figure 1 is a perspective view of a tear-off plate embodying the invention and shows how a sheet may be severed thereon; Fig. 2, a plan view of the plate; and Fig. 3, a trans- 30 verse vertical sectional view taken as indicated at line 3 of Fig. 2.

In the construction illustrated a base-plate 10 is provided with four resilient domes or legs 11. The plate may be made of sheet steel 35 if desired, 16 gauge being satisfactory. Two adjoining marginal edges of the base-plate are provided with narrow guide-strips 12 which also serve as spacing and supporting means for the top-plate or templet 13.

40 The templet 13 has the contour of the area to be torn out. It is fixedly mounted on the guide-strips 12 and extends outwardly over the base-plate to form a paper-admitting slot 14. The free edges of the templet are bevelled as shown at 15 to provide sharp tearing edges which meet at a point 16 which initially pierces the sheets during the severing operation. The templet is provided with a finger-opening 17 through which the operator holds 45 the strips against the base-plate during the

tearing operation and is also helpful in removing the severed area from the slot 14 after severance.

To use the device, the forms are inserted 55 between the templet and base plate and aligned by means of the guide-strips, the operator holds the forms with his thumb or finger in the opening 17 and pulls the ticket against both edges simultaneously.

If desired, the guide-strips 12, which also 60 serve as spacing means for the top-plate, may be of a resilient material such as rubber which will permit the top-plate to be pressed against the base-plate and grip an interposed slip. The top-plate is made of steel, prefer- 65 ably, and while it is resilient enough itself to permit sufficient bending to grip an interposed slip, using the mounting shown, it is preferred to provide a finger-opening for that purpose. 70

By using the device the label is torn out very quickly and cleanly and without danger of mutilating the label itself or the invoice. The operation is much quicker in 75 tearing even one label than is the old practice of tearing around a perforation, and when six or eight forms are put into the device and torn at one operation, the saving in time is substantial.

The foregoing detailed description has 80 been given for clearness of understanding only, and no unnecessary limitations should be understood therefrom, but the appended claims should be construed as broadly as permissible, in view of the prior art. 85

What I regard as new, and desire to secure by Letters Patent, is:

1. In combination: a base-plate provided with supporting legs, and having guide-strips on at least two of its marginal edges 90 portions to facilitate positioning of a paper-sheet on said base-plate; and a top-plate fixedly mounted on said guide-strips in spaced relation to said base-plate so as to overlie a sheet resting thereon, the edges of said top-plate which extend over said sheet being sharpened to form tear-off edges, and said top-plate being provided with a finger-opening through which the sheet may be gripped during a tearing-operation. 95 100

2. In combination: a base-plate; a top-plate fixedly mounted thereon in spaced relation so as to provide an intervening slot into which a sheet of material may be inserted for severance, said top plate having a tear-off edge and being provided with a finger-opening to permit the sheet to be gripped during a tearing-operation; and guides within said slot to position said sheet when fully inserted therein.

JOHN E. EUTH.
